UNITED STATES PATENT OFFICE.

ADOLF FRANKE, OF BERLIN, GERMANY.

TYPE-PRINTING TELEGRAPH.

SPECIFICATION forming part of Letters Patent No. 665,734, dated January 8, 1901.

Application filed January 18, 1899. serial No. 702,533. (No model.)

To all whom it may concern:

Be it known that I, ADOLF FRANKE, a subject of the German Emperor, residing at 94 Markgrafenstrasse, Berlin, S.W., German Empire, have invented certain new and useful Improvements in Type-Printing Telegraphs; and I do hereby declare the following to be a full, clear, and exact description of the invention, such as will enable others skilled in the art to which it appertains to make and use the same.

This invention relates to type-printing telegraphs.

The invention consists in the herein-described apparatus.

Of the accompanying drawings, Figure 1 is a diagrammatical illustration of my improved apparatus as it is used with continuous currents. Fig. 2 is a detail view of parts, and Fig. 3 is a diagrammatical illustration of the apparatus as it is used with alternating currents.

The same characters of reference indicate the same parts in all the figures.

a, Fig. 2, is a shaft on which the type-wheel B is firmly mounted. Besides the type-wheel the escapement-wheel C is likewise mounted firmly on the shaft a and is provided with a rigid arm L, projecting radially between two pins fastened in a toothed wheel J, loosely mounted on the shaft a. Lastly, a projecting nose or cam N^a is rigidly fastened on the said shaft a. All these parts are shown beside each other in Figs. 1 and 3 for the sake of clearness. As will be seen in these figures, a lever D, provided with an anchor at one end, engages with the escapement-wheel C. The lever D is pivoted in b, and its free end is made to form the armature of a polarized electro-magnet E. The radial extension L is provided with a spring M, which also engages with the pins N^a and N^b, thus forming an elastic coupling between the wheels C and J. The teeth of the wheel J are adapted to lift a contact-spring K, which when released engages with the contact k⁸. The shaft a is surrounded by a ring provided with pins s, such as is employed usually in the Hughes apparatus.

A, Figs. 1 and 3, represents a casing containing a spring, which is supposed to drive

the shaft a by means of wheel-gearing in the usual way.

P is an operating-key which makes contact with k⁶ and k⁷ when it is depressed, and at the same time by means of the sliding bar Q operates the three-armed lever R, causing it to touch either of the contacts k² or k⁴. The free arm of this lever R in its turn engages with the lever T, pivoted in e, and resting on the nose N^a, fixed on the shaft a and adapted to make contact with k⁵.

The lever G carries at its end a printing-roller and is operated by the electromagnet F. It engages with the arm d', pivoted in c and being rigidly connected with the arms U and S. The arm U rests on the edge of the cylindrical spring-casing A with so much friction that it is moved in the direction of the rotation indicated by the arrow when it is released. The arm S carries the spring W, adapted to engage with that part of the lever R which projects below the pivot.

H represents an ordinary line-relay operating the contact-lever h, so as to make it touch either of the contacts k¹ or k³.

Z' Z² Z³ Z⁴ Z⁵ Z⁶ Z⁷ are binding-posts.

L' and L" are conductors leading into the line.

LB is the line-battery, the two halves of which, OB' and OB², are arranged to be used as local batteries.

V is a switch by means of which a telephone is supposed to be placed in circuit in case the direct transmission of speech is preferred, when it is turned into the position indicated by X.

1, 2, 3, 4, 5, 6, 7, 8, 9, 10, 11, 12, 13, and 14 are conductors connecting the different parts of the apparatus.

The object of this apparatus is to represent a simple type-printing telegraph so constructed that the same apparatus can be used as transmitter and as receiver and that the transmitter can be operated by manipulating a number of keys corresponding to the different letters and signs of the ordinary alphabet. In order that such an apparatus may be adapted to be used by any untrained person, it is necessary that the apparatus itself and its operation should be of the simplest possible description and that it should return

automatically into the original position when the operators have ceased to use it.

For the sake of clearness the operation of my apparatus will be described at first as if it were only meant to act as a transmitter.

- When the apparatus is at rest, all the parts are in the positions shown in the drawings. The contact-arm h of the relay H touches contact k' , R touches k^3 , P touches k^6 , T is lifted off k^5 by the nose N^a , and K is lifted off k^8 . When the apparatus is to be put in action, the operator at the transmitting-station only has to depress the button P of his apparatus, whereby the line-current is closed. When the key P is depressed, first the contact k^6 is broken and then the contact k^7 is closed. Thereby a current is caused to flow from the positive terminal of the line-battery LB to the binding-post Z^5 and through the line L' to the receiving apparatus. After passing through the latter the current returns through L'' , passes over binding-post Z^4 , conductor 1, switch V , conductor 2, the winding of the electromagnet of the relay H , conductor 3, the key P , contact k^7 , conductor 4, and over the binding-post Z^1 back to the negative terminal of the battery. The relay thereby is caused to attract its armature, and thus to close a local circuit, in which a current starts from the positive terminal of the local battery OB' over binding-post Z^5 , conductor 5, k^2 , h , conductor 6, electromagnet E , conductor 7, printing-magnet F , conductor 8, and returns over Z^6 to the battery. This current causes the printing-lever G to be attracted and by means of the arm d' moves the lever S , pivoted in c , and thereby causes the contact-lever T to touch the contact k^5 . As N^a is released the clockwork begins to rotate. Furthermore, it should be remarked that the lever D is not moved by this means, because the direction of the current is the same as that of the current which has last passed through the polarized electromagnet, and therefore cannot cause the armature to be shifted. Since currents of different directions are used, means are provided to cause the last current always to flow through the apparatus in the same direction as the first that has passed through it. When the button P is fully depressed, the contact-lever R is shifted from contact k^8 to contact k^4 by means of the sliding bar Q and remains in this position as long as the operation of the apparatus lasts. When the key P is released, contact is again made between P and k^6 , and likewise h returns to k' . Therefore a local current is caused to flow from the positive terminal of the battery OB^2 , over the binding-post Z^6 , through 8, F , 7, E , 6, h , k' , 9, k^5 , T , 10, 4, and over Z^7 back to the negative terminal of OB^2 . By means of this current passing through E the lever D is operated, the shaft and with it the clockwork is released, and by the motion of J , K is caused to touch k^8 . By this means simultaneously a line-current is caused to flow

from the positive terminal of the line-battery LB over Z^5 Z^2 L' , the receiver apparatus L'' , Z^4 , 1, V , 2, relay H , 3, P , k^6 , 11, R , k^4 , 12, K , k^8 , 13, 4, and back over Z^1 to the negative terminal. By this current the armature H is attracted, h is caused to touch k^2 , the armature D is shifted, and by means of the rotation of the shaft a thus caused K is lifted off k^8 , whereby the line-current is interrupted and the contacts in the relay H are again changed. The same process is repeated over and over again until no further key is touched.

It should be remarked that the printing-magnet is prevented from fully attracting its armature by the quickness with which the current changes, so that the paper is not brought into contact with the type-wheel.

If now a letter-key—as, for example, X' , Fig. 2—is depressed, one of the pins s of the disk is lifted by the key-lever in the same manner as in the Hughes apparatus. This pin intercepts the motion of the extension O , fastened to the wheel J , and arrests the wheel, and thereby likewise brings the shaft a to a standstill. The latter, however, since it is not rigidly coupled with J , can continue in its rotation as far as the space between the pins N' and N^2 admits. The spring M is hereby depressed. By arresting the driving-shaft the following operations are caused: Supposing the shaft is arrested when K is making contact with k^8 , a line-current is made to flow from the positive terminal of the battery LB over Z^5 , L' , the receiver L'' , 1, V , 2, 100 H , 3, P , k^6 , 11, k^4 , 12, K , k^8 , 13, 4, and back over Z^1 to the negative terminal of the battery. By this current the relay H is operated, k^1 is replaced by k^2 , and the local current of the battery OB' is started. The electromagnet E thereby operates the armature D , and G is attracted by F . Thus since a current of longer duration can pass through F during the stoppage the letter which happens to be placed opposite the printing-roller will be 105 printed off, because G can be fully attracted. After the letter-key has been released the relay and the contact-wheel J in turn will again make contacts until the extension O strikes another pin s . If O is arrested while 110 the contact between K and k^8 is interrupted, exactly the same operations will be caused, with this difference only, that the local current issues from OB^2 . In the receiver the action of the current is for the most part 115 analogous to that of the transmitter, with this difference only, that the operation of the starting-key is omitted and that therefore the lever R is not shifted. After the button P of the transmitter has been depressed a 120 current is first sent through the line L' , passes over Z^3 into the receiver, and goes through conductor 14, k^8 , R , 11, k^6 , P , 3, relay H , 2, V , 1, Z^4 , and returns over L'' to the transmitter. The armature of H is attracted, and 125 h is made to touch k^2 . By this means first the local circuit of OB' is closed just the same as 130

in the transmitter. A current consequently flows from the positive terminal of OB' over Z^5 , 5, k^2 , h , 6, E, 7, F, 8, Z^6 , and back to the negative terminal of OB' . By this current G is attracted and S is shifted so as to bring the arm T into contact with k^5 , and now both the local circuits can come into action in turn, as has been explained with reference to the transmitter, and will operate the two armatures D and G.

The elastic coupling between the type-wheel and the contact-making arrangement is provided in order to insure exact synchronism between the two type-wheels while the printing proceeds. If the shaft was rigidly coupled with the contact arrangement, the following action would take place:

Supposing that in the transmitter O has struck one of the pins s and that K is lifted off from k^8 , then h touches k' , and thereby closes the local circuit of OB^2 . Thus a current is passed through this circuit, by which F and E are excited, and consequently D is shifted and will release the shaft. However, since the latter is arrested by s it cannot turn. In the receiver this is different, because here the arm O does not strike any of the pins s, and therefore can continue to turn over one more letter until it is arrested by the anchor D. Therefore the transmitter would lag behind to the amount of one letter. If, however, the shaft is coupled loosely with the contact arrangement, though the latter be arrested the type-wheel will be free to move forward as far as that of the receiver.

When the key P of the transmitter has once been depressed, both instruments would continue to run down as long as the clockwork admits; but by the following arrangement they will throw themselves out of circuit automatically and will return into the position of rest. For this purpose the elastic arm or spring U is fixed on the lever S, which rests against the circumference of the spring-casing A with just enough friction to cause it to be carried along with the movement of the casing.

When the starting-key P is depressed and also when any successive key is touched, the lever S is turned around c by means of the printing-lever G and arm d'. Hereby U is also moved a certain distance along the circumference of the spring-casing A in the sense opposite to the rotation of the latter. When the clockwork begins to run, U is carried back by the casing A. The dimensions are so chosen that S will return into its original position after several turns of the type-wheel. Then the nose N^a will break the contact between T and k^5 , and at the same time R will be brought back into its original position. Thus all connections are severed and the instruments are brought back into their position of rest.

In order to be quite sure that all connections in the receiver have been separated be-

fore those of the transmitter are interrupted, an arrangement is provided by which the receiver is arrested after two turns of the shaft, the transmitter, however, not before three revolutions. This object is obtained by the circumstance that in the transmitter and the receiver the lever S is shifted only a certain distance by the printing-lever G, and thereby the spring W, fastened to the arm d' of the lever S, is depressed. Whenever in the transmitter the lever R touches k^4 , in the receiver it touches k^8 . Consequently in the receiver the spring W is depressed, and in the transmitter it moves freely. In the receiver the spring W being depressed will cause the lever S to return a certain distance, corresponding to the depression of the spring after the lever G has been lowered, and thereby a difference between the positions of the two levers S in the two instruments always remains, and thereby the receiver is made to return into its original position after two revolutions of the type-wheel, and the transmitter not before three revolutions have been completed.

The transportation of the paper can be managed by any one of the known methods and is not described, because it is no important part of this invention.

When the instruments herein described are to be operated with alternating currents on the line some slight modification must be provided. The relay H must be arranged for alternating currents, and some alterations must be introduced into the contact-making arrangement, which are shown in Fig. 3. The same apparatus is again either used as transmitter or as receiver; but it will be seen that the arrangement of the connections is altered in such a way that the relay of the transmitter remains at rest, and the printing and starting magnets are connected in parallel with the line-circuit and are operated as follows: When at rest, all parts take the positions shown in the drawings. By depressing the starting-key P again both instruments are put into action. At first the lever S is rotated around c by means of an arm x of the sliding bar Q, and thus contact is made between T and k^7 . By depressing the starting-button P still more the lever R is again operated. In this case it changes two contacts— r' touches k^4 , and r^2 touches k^8 . Thus two circuits are closed. The one circuit is composed by the transmitter, the line, the receiver, and the return-line. The other one is a local circuit which is connected in parallel with the line-circuit. The main circuit starts from the positive terminal of LB' , passes over the binding-post Z^6 , 1, 2, k^6 , r^2 , 3, Z^8 , line L' , the receiver, line L'' , Z^4 , 4, V, 5, 6, K, k^8 , 7, 8, Z^5 , and back to the negative terminal of LB' .

The path taken by the current in the receiver will be described hereinafter.

The shunt-circuit is composed as follows: Positive terminal of LB' , Z^6 , 1, 9, F, 10, E, 11, r' , k^4 , 12, K, k^8 , 7, 8, Z^5 , and back to the nega-

tive terminal of LB'. This shunt-current operates E, because the direction of this current is opposed to that of the preceding current that has passed the magnetic system, and therefore the contact of the spring K is changed and contact is made between K and k^9 . By this means a current of opposite direction is sent from the battery LB'' through the line, as well as through the shunt. The line-current issues from the positive terminal of the battery LB'', passes over Z⁷, 13, T, k^5 , 14, 15, k^6 , K, 6, 5, V, 4, Z⁴, L'', the receiver L', Z³, r², k^6 , 2, 1, Z⁶, and back to the negative terminal of LB''. The current in the shunt runs as follows: positive terminal of LB'', Z⁷, 13, T, k^7 , 14, 15, k^9 , K, 12, k^4 , r', 11, E, 10, F, 9, 1, Z⁶, negative terminal of LB''. The current again passes E in the opposite direction, and therefore operates D, whereby the shaft of the type-wheel is allowed to turn. Hereby K is again brought into contact with k^8 , and the same play is repeated over again. From what has been explained it will be seen that an alternating current flows through the line and only becomes a current of longer duration when the shaft of the type-wheel is arrested by one of the pins s by the depression of a letter-key in the manner described, whereupon the printing-lever presses the paper against the type-wheel.

The path of the current in the receiver runs as follows: When the starting-key is depressed, the current enters the receiver over line L'. Here it passes over Z³, 3, r², k^5 , 16, H, 17, 5, V, 4, Z⁴, and returns over L'' to the transmitter. Hereby H is put in action, and the arm h is made to touch k^2 , and thus a local current is closed which issues from the positive terminal of LB', passes over Z⁶, 1, 9, F, 10, E, 11, r', k^3 , 18, h, k^2 , 19, 8, Z⁵, and back to the negative terminal of LB'. By this means the electromagnet E is put in action, because this current passes it in a direction opposed to that of the preceding current, and both instruments run in synchronism. In the receiver naturally the connection of T with k^1 is not made by means of the key P, but rather by the printing-magnet, which causes G to lift the arm d², as has been described above. If now a current passes the relay H in the opposite direction, the contacts in the relay are changed, and those belonging to the shaft of the type-wheel likewise, and the same play is repeated as described above, only in inverted order. The other functions of the apparatus are exactly the same as in the apparatus operated by continuous current.

Having now particularly described and ascertained the nature of the said invention and the manner in which the same is to be performed, I declare that what I claim is—

1. In a type-printing telegraph, the combination, with a type-wheel, a contact device, an escapement-wheel, a shaft on which said

type-wheel, contact device and escapement-wheel are mounted, and an anchor engaging the escapement-wheel, of an electromagnet controlled by the contact device and arranged to govern the anchor, and resilient means for permitting the type-wheel to move a predetermined amount after the contact device is stopped, and for returning the contact device to its normal position relative to the type-wheel after said contact device has again started in operation. 75

2. In a type-printing telegraph, the combination with a type-wheel, a contact device, an escapement-wheel, a shaft on which the said type-wheel, contact device and escapement-wheel are mounted, and an anchor engaging the escapement-wheel, of an electromagnet controlled by the contact device and arranged to govern the anchor, and a resilient coupling between the contact device and type-wheel, whereby the latter is allowed to turn to a limited extent after the contact device has stopped and the latter is returned to its normal position relative to the type-wheel, when said contact device has again started in operation. 85

3. In a type-printing telegraph, the combination with a type-wheel, a shaft on which the same is fixed, and a contact device, of an escapement-wheel fixed to said shaft, electromagnetic means for operating said escapement-wheel to rotate the same, a circuit in which said electromagnetic means and the contact device are included, means for energizing the circuit, mechanism for positively stopping said contact device, and a resilient flexible coupling device intermediate the shaft and the contact device, whereby the escapement-wheel and the type-wheel may have a movement relative to the contact device after the latter is stopped and the said contact device, when released, will be returned to its normal position relative to the shaft and type-wheel. 95

4. In a type-printing telegraph, the combination with a transmitter type-wheel, a shaft on which the same is fixed, a contact device loosely mounted on said shaft, and provided with a pair of stops, an escapement-wheel fixed on the shaft and provided with an arm projecting between and capable of lateral motion with relation to the stops on the contact device, a spring between said arm and one of the stops, an anchor engaging the escapement-wheel, an electromagnet arranged to operate the anchor, a circuit in which the said electromagnet and the contact device are included, and means for energizing the said circuit. 110

5. In a type-printing telegraph, the combination, with a type-wheel, a contact device, an escapement-wheel, a shaft on which the said type-wheel, contact device and escapement-wheel are mounted, and an anchor engaging the escapement-wheel of an electro- 125

magnet controlled by the contact device and arranged to govern the anchor, means for arresting the type-wheel upon the depression of a letter-key, a lever, a clockwork for driving the instrument, means operated by the clockwork for moving said lever, a printing-lever, means for returning said lever to its normal position, upon the operation of the printing-lever, a contact device connected to said le-

ver, and a nose on the type-wheel shaft arranged to actuate the latter contact device.

In testimony whereof I have affixed my signature in presence of two witnesses.

ADOLF FRANKE.
